United States Patent Office.

PHILIP SUM, OF NEW YORK, N. Y.

Design No. 2,987, dated March 31, 1868.

DESIGN FOR A SHOW-CASE MOULDING.

The Schedule referred to in these Letters Patent and making part of the same.

TO ALL WHOM IT MAY CONCERN:

Be it known that I, PHILIP SUM, of the city, county, and State of New York, have invented a new and improved Design for Show-Case Mouldings; and I do hereby declare that the following is a full, clear, and exact description thereof, which will enable others skilled in the art to make and use the same, reference being had to the accompanying drawings, forming a part of this specification, in which—

Figure 1 is a plan view of my new show-case moulding.

Figure 2 is a vertical transverse section of the same.

Similar letters of reference indicate corresponding parts.

This invention relates to a new show-case moulding, which is fully illustrated in the accompanying drawing. It has five main mouldings or sides, *a*, *b*, *c*, *d*, and *e*. The outer sides, *a* and *e*, are ogee mouldings, with their convex portions nearest to the respective horizontal and vertical walls of the show-case, while their concave portions touch the respective mouldings *b* and *d*. Each of these consists of two concave divisions of equal width, so that they have a projecting rib in their middle. The middle side *c* is concave, as shown, and forms ridges at its junctions with the mouldings *b* and *d*. A very simple and still elegant moulding is thus produced.

Having thus described my invention, I claim as new, and desire to secure by Letters Patent—

The design for show-case moulding herein set forth and shown.

PH. SUM.
